UNITED STATES PATENT OFFICE.

PAUL S. KNITTEL, OF JERSEY CITY, NEW JERSEY.

PULVERIZING MACHINE.

Application filed May 18, 1927. Serial No. 192,307.

This invention relates to the pulverizing machines illustrated in the Roebbel Patent 1,015,844, dated Jan. 23, 1912 and my own Patent 1,424,922, dated Aug. 8, 1922 wherein 5 a series of rings and hammers are rotatably mounted within the casing.

In a pulverizer of these types the grinding rings are loosely mounted on their supporting rods their diameter depending on the size of 10 the machine. As this size is very limited, the actual grinding surface in contact with the stationary grinding concaves in the machine is also very limited corresponding to the diameter of the rings. Therefore, with 15 ring sectors as described hereinafter having a surface arcuated by a radius equal to the diameter of the ring suspended from the same point as in the above mentioned patents, the contact between the triangle grinding members and the grinding concaves is increased 20 proportionately. In pulverizers as described in the above patents, it is found that the rings are worn one-sided and remaining in one position during the grinding operation so that 25 the worn side only acts as grinding surface, the part of the ring still containing the original dimension not coming in contact with the material to be ground. Extreme cases have shown that one side of the ring can be 30 ground completely away where the other parts of the ring remain nearly their original dimension.

The triangle grinding members as herein-after described will force the least worn and 35 heaviest grinding surface against the grinding concaves on account of the centrifugal and gravity action. The gravity action taking place at the starting and stopping of the machine or when the grinding member is 40 lifted off the point of suspension on account of striking foreign parts contained in the material to be ground. This centrifugal action is the action of the machine proper when running.

45 The principal object of the present invention is to produce a grinding member which will give a more economical grinding surface and prevent a one-sided wear of the grinding members. Other objects are an increase of 50 the wearing surface in proportion to the weight of the grinding member. It further consists in the arrangement and combinations herein described and claimed.

55 In the accompanying drawing wherein like reference numerals refer to like parts wherever they occur,

Fig. 1 is a vertical transfer section through a pulverizer provided with grinding sectors embodying my invention,

Fig. 2 is a detail perspective view of one of 60 the grinding members shown in Fig. 1.

Figs. 3, 4, 5 and 6 are cross sections through the grinding member showing the different forms of grinding surfaces possible and required for different purposes. 65

Referring to Fig. 1 of the accompanying drawing, my invention is illustrated in connection with a pulverizer comprising an upper casing 5 and a lower casing 6 having removable sections 7 for clamping them together. 70 The main shaft 8 is mounted in bearings formed in the end walls of the lower casing. Each end wall of the lower casing is provided with a flange 9 which supports the ends of the grinding concave 10 and the grate bars 11. The end walls of the lower casing are secured together by means of rods 12 located inside the casing below the grinding concave and the grate bars. Mounted on the shaft 8, in the recess formed in the inner face of the end walls of the casing, are end plates or disks 13. These disks are keyed to the shaft 8 so as to be rigid therewith and are connected to each other near the outer edge by a series of spaced parallel rods 14. 75

Arranged on the series of rods 14 are grinding sectors 15 and shredding or cutting sectors 16. Mounted on the shaft 8 between the disks 13 are spiders 17, whose radially extending arms 18 are perforated to receive the supporting rods 14, thereby forming supports for said rods intermediate their ends. The radially extending arms 18 of the spiders 17 serve to space the grinding sectors 15 and the shredding sectors 16 which are arranged in alternation on the supporting arms. This same arrangement of spacing is carried out in the angular spacing of the grinding sectors and the shredding sectors on the supporting rods 14. The hub portions of the spiders are 100 keyed to the shaft 8 and abut against each other, thereby spacing the arms of the spiders the desired distance from each other. 105

According to the requirements of the machine, the sectors may be equipped with smooth surfaces Fig. 3, wedge formed surfaces Fig. 4, hammer formed surfaces Fig. 5 and narrow blade surfaces Fig. 6. Any other form can be given to the outside of the grinding sectors as may be found necessary in the future. 110

The form of grinding sector as shown in

Fig. 2 is the triangular form in which the three sides are arcuated from the suspension points, making the radius equal the diameter of any grinding ring possible in the same size machine. In addition to triangularly formed grinding sectors, forms with more suspension points can be used, but I found that the triangular form will give the largest grinding surface. A grinding sector with two suspension points is not advisable as the same will not readily yield when foreign material should be contained in the machine.

In the operation of the machine, it is found that the grinding sector will lean back so that the front point of each arcuated part will do the actual work, the rear part will be lifted away from the grinding concaves 10 and therefore preserved. It, therefore, is possible to turn the grinding sectors end for end so that the point being before the rear part will now work as front part and give a new sharp grinding surface. The change from one arcuated surface to the other will take place when the wear is sufficient to give the difference in the gravity action which takes place when starting or stopping the machine or when foreign material is contained in the machine. In starting the machine, the sectors will swing on the suspension point until the velocity increases and the sectors are thrown out by centrifugal force. Passing over the highest part in the revolving circle, a velocity is reached where the gravity action on the sectors is still sufficient to overcome the centrifugal action of the machine and the sectors will drop down so that another arcuated face is exposed to the grinding concaves 10. This is noticeable in the machines by the sound of the falling sectors.

When foreign material strikes the sector,

the same is lifted off the suspension point. The forward movement of the machine brings the suspension point of shaft 14 to a position so that the other suspension point in the grinding sector is caught by the shaft 14 and another grinding surface is exposed to the grinding concaves 10.

From the foregoing description, it will be seen that the grinding sectors have many advantages over the standard ring and will allow an increased thickness of the grinding surfaces so that a larger proportion of the total weight of the grinding members can be used. For this purpose, the shaft 14 is made of especially large diameter and after the grinding surfaces are worn away, a smaller shaft is used instead of the original large size shaft 14, allowing the grinding sector to approach again, the grinding concave 10, to the original distance.

The foregoing arrangement is considered only as an example; and I do not wish to be limited to the type of machine shown as my crushing and grinding member is equally as well applicable to other types of pulverizers.

What is claimed is:

A crushing and grinding member for pulverizing machines comprising a substantially triangular annular body for suspension from the inner angles thereof, the sections of said body between its apices being of equal mass and of the same form, and each of said sections having an exterior grinding surface extending between spaced apices on an arc whose center lies substantially in the opposite inner angle of the triangular body, said grinding surfaces being connected with each other at the apices of said member by convex surfaces.

PAUL S. KNITTEL.
